[57] CLAIM

The ornamental design for a van top, as shown and
described.

DESCRIPTION

FIG. 1 is a perspective view of the van top showing our
new design, it being understood that the portion shown
in broken lines is for illustrative purposes only and
forms no part of the claimed design.

FIG. 2 is a top plan view thereof;

FIG. 3 is a left side elevational view thereof, with the
right side being substantially a mirror image of that
shown;

FIG. 4 is a rear elevational view thereof.
